UNITED STATES PATENT OFFICE

CHARLES T. SHOEMAKER, OF PHILADELPHIA, PA., ASSIGNOR TO HENRY DISSTON, HAMILTON DISSTON, AND ALBERT H. DISSTON, OF SAME PLACE.

IMPROVEMENT IN DEVICES FOR HAMMERING SAWS.

Specification forming part of Letters Patent No. **152,872**, dated July 7, 1874; application filed June 20, 1874.

To all whom it may concern:

Be it known that I, CHARLES T. SHOEMAKER, of Philadelphia, Pennsylvania, have invented an Improvement in Hammering Saws, of which the following is a specification:

The object of my invention is to dispense with much of the skilled labor required in hammering the blades of handsaws, by subjecting them to the action of a power-hammer the head of which is of the same area and conformation, and, when the blow is struck, always coincides with the face of the anvil, as shown in Figure 1 of the accompanying drawing.

It will be proper to remark in the outset that the blades of handsaws are hammered after they have been tempered, ground, and polished, and after the teeth have been cut on the edges. The object of this hammering is to slightly expand the metal at and near the middle of the blade, so as to impart a tension and consequent stiffness to the edges of the same.

The dotted lines in Fig. 2 illustrate the direction of the blows, which are, according to the present practice, imparted by a hand-hammer of the character shown in Fig. 3, the blade being placed on an anvil, D, the face of which is necessarily larger than that of the hammer-head in order that the workman may perform his duty properly.

Owing to this difference between the hammer and anvil, every blow on the blade has a tendency to bend it; hence the operator must repeatedly reverse the blade, must examine it at frequent intervals, and apply straight edges until it is perfectly straight. This oper-

ation is one demanding much skill and experience at the hands of well-paid workmen, and my object is to dispense with much of this skilled labor.

In Fig. 1, A is a hammer so driven by power that it is caused to rise and fall rapidly in suitable guides. This hammer has a head with a slightly-rounded face, *a*, and immediately below this face is the similar face *b* of the anvil.

I have ascertained by practical tests that if the face of the hammer and that of the anvil are of the same extent and conformation, and that if one always coincides with the other when the blow is struck, there will be but little bending of the blade, the latter after it has been subjected to this hammering operation demanding but little skilled labor.

The hammer *a* and anvil *b* may be made solid, as shown in Fig. 1, or they may consist of plugs or pins adapted to sockets in the hammer-head and anvil-body, and retained therein by set-screws or otherwise, as shown in Fig. 4.

I claim as my invention, and as an improvement in the art of hammering saw-blades—

Subjecting them to the action of a power-driven hammer having a face conforming in shape to and coinciding with that of the anvil, as set forth.

In testimony whereof I have signed my name to this specification in the presence of two subscribing witnesses.

C. T. SHOEMAKER.
